UNITED STATES PATENT OFFICE

HERBERT J. CRABBS, OF IRWIN, PENNSYLVANIA, ASSIGNOR TO WESTINGHOUSE ELECTRIC & MANUFACTURING COMPANY, A CORPORATION OF PENNSYLVANIA

DISCONNECTING SWITCH MECHANISM

Application filed February 17, 1928. Serial No. 254,975.

My invention relates to disconnecting switches and particularly to disconnecting switches of the double-throw type wherein means are provided for releasably retaining 5 the disconnecting-switch blade in either of its operative conducting positions.

An object of my invention is to provide a multiple-blade disconnecting switch wherein in each blade comprises a pair of blade members spaced apart and yieldingly biased toward one another for yieldingly engaging a contact jaw that extends between the blade members, and to provide a disconnecting switch of this type with a single latching 15 unit that may be of standard construction and which may be used on single disconnecting switches of the multiple-blade-member type.

A further object of my invention is to 20 provide a disconnecting switch having the above-noted characteristics, wherein a positioning member corresponding to the end of a single-type switch blade is disposed between the blades of the disconnecting switch and which cooperates with a latch mechanism that may be applied to a single switch blade.

A further object of my invention is to 25 provide a latch for a double-throw disconnecting switch comprising two complementary members having overlapping hooks thereon which constitute an eyelet for receiving a hook stick.

These and other objects that will be made 30 apparent throughout the further description of my invention are attained by means of the apparatus hereinafter described and illustrated in the accompanying drawing, wherein.

40 Figure 1 is an elevational view of a portion of a double-throw disconnecting switch embodying features of my invention,

Fig. 2 is a top plan view of a fragment of the structure shown in Fig. 1,

45 Fig. 3 is a plan view of a portion of a multiple-blade disconnecting switch showing the latch mechanism applied thereto.

Figs. 4 and 5 are elevational and plan views, respectively, of the latch shown in 50 Figs. 1 to 3, and

Fig. 6 is an elevational view of a positioning plate that constitutes a part of my invention.

Referring to the drawing and particularly to Figs. 1 and 2, a single-pole double-throw disconnecting switch is illustrated comprising a supporting base 7 on which are mounted insulating pillars 8 and 9 of the usual type, the pillar 8 supporting a pivot jaw 11, and the pillar 9 supporting a switch 60 contact jaw 12. It will be understood that a third pillar, corresponding to the pillar 9, is mounted on the base 7 beneath the pillar 8 and supports a switch contact jaw 12 similar to the jaw shown in the figure. 65

A double-throw multiple switch blade 13 comprises blade members 14 which are pivotally mounted on opposite sides of the pivot jaw 11. The blade members 14 are spaced apart, intermediate their ends, by spacer members 15 that are retained in position by hollow rivets 10, and the blade members are yieldingly biased toward one another by spring washers 16 that are mounted exteriorly of the blade members and secured in 75 place thereon by a bolt 17.

The switch jaw 12 is provided with a slot 18 for receiving the bolt 17 and permitting movement of the switch blade 13 into full engagement with the contact jaw 12, as indicated in 80 Fig. 1. The spring washers 16 serve to yieldingly press the blade members 14 into engagement with the switch jaws 12 when the latter is in closed position.

In order to retain the switch blade in closed 85 position, a catch 19, having a shoulder 21, is mounted on the contact terminal 22 adjacent to the contact jaw 12, and a pair of latch members 23 and 24 are pivotally mounted on the free end of the blade member 13 by means 90 of a bolt 25 that extends through the ends of the blade members 14 in alignment with the spacers 15.

The latch members 23 and 24 are complementary and interchangeable and are provided with hubs 26 that are disposed on the outer sides of the blade members 14, as indicated in Fig. 2. The latches are provided with recesses 27, (Figs. 2, 4 and 5), which serves to retain a spring 28 that is attached, 100

at its ends, to the latch members 23 and 24, as indicated in Fig. 2, the spring serving to draw the outer ends of the latch members toward one another in order that a shoulder 29, formed on each of the latch members, shall be yieldingly pressed into engagement with the shoulder 21 of the catch 19 to retain the blade 13 in closed position.

Each latch is provided with a shoulder 31 (Figs. 1 and 4) that seats upon the outer end of the catch 19 when the switch blade 13 is in closed position, and an offset shoulder 32 on each latch is provided for limiting the movement thereof with respect to the blade member by engagement with the free end thereof. Each latch is provided with a bent hook portion 33 which cooperates with the hook portions of its complementary member to constitute an eyelet 34 in which a hook stick (not shown) of the usual type may be inserted for operating the switch blade and the latches.

Referring to Fig. 1, in order to open the disconnecting switch 13, a hook stick is inserted in the eyelet 34, and the latch 23 is pulled outwardly thereby. Movement of the latch 23 withdraws the shoulder 29 thereof from engagement with the shoulder 21 of the catch, which permits the withdrawal of the switch blade from the contact jaw when the latch member 23 is further pulled outwardly. As previously stated, the outward pivotal movement of the latch 23 is limited by reason of engagement of the shoulder 32 thereof with the extreme end of the switch blade 13.

When the double-throw disconnecting switch blade 13 is moved into engagement with the lower contact jaw 12, referred to as constituting a part of the disconnecting switch, the latch 24 functions to retain the switch in closed position with that jaw.

In Fig. 3, I have shown a multiple-blade disconnecting switch which comprises a pair of multiple-blade members of the type illustrated in Figs. 1 and 2. In the multiple-blade construction shown in Fig. 3, two switch jaws 12 are mounted on the insulator 9 in spaced relation and each is engaged by a multiple disconnecting switch blade 13 similar to that shown in Fig. 1. A single bolt 17 serves to tie the switch blades 13 in fixed spaced relation, and the latch members 23 and 24 are mounted on a bolt 25 that connects the free ends of the blades 13, the latches being mounted between the blades 13, as indicated in Fig. 3.

Since the latch members 23 and 24 are not, in this case, mounted on opposite sides of a blade 13, but, instead, are mounted between two blades 13 that are spaced apart, a positioning member 35 (Figs. 3 and 6) is provided for the latch members and is mounted on the bolts 17 and 25 in such manner that it is rigidly supported between the switch blades 13, the hubs 26 of the latch members being

disposed on opposite sides of the positioning member 35 which is provided, adjacent to the point of contact with the latch members, with a boss 36.

The shoulders 32 of the latch members engage the outer edge 37 of the positioning member 35 for limiting the movement of the latch members in the same manner that the free end of the switch blade 13 of Figs. 1 and 2 serves to limit movement of the latch members.

By reason of this construction, latch members for a single multiple-blade-member disconnecting-switch blade, such as is shown in Figs. 1 and 2, may serve to constitute a latch without necessitating any change of construction in the design of the latches or the blade members 14 that constitute the switch blade 13. The only additional part required in so adapting the latches is the positioning member 35. The lengths of bolts 17 and 25, however, must be increased to accommodate the greater width of switch-blade structure.

While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. A disconnecting switch comprising a pair of spaced switch blades, switch jaws for engaging the blades, a catch member adjacent to the jaws, a latch for engaging the catch member carried by the blades and comprising a pair of pivoted latch members having hub portions spaced apart and carried on a single pivot on the blades, and a latch-positioning member disposed between the said hub portions adapted to retain the latch in a predetermined position between the said switch blades.

2. A disconnecting switch comprising a switch-blade member, a contact jaw, a catch member adjacent to the jaw, and a pair of complementary latches pivotally mounted by a single pivot means on the blade member and having overlapping hook portions constituting an eyelet for receiving a hook stick.

3. A switch comprising a pair of spaced switch blades, a single shaft connecting said blades, switch jaws for engaging said blades, a latch comprising two movable latch members mounted on said shaft, and a catch for engaging said latch.

In testimony whereof, I have hereunto subscribed my name this 13th day of February, 1928.

HERBERT J. CRABBS.
